UNITED STATES PATENT OFFICE.

GEORGE W. BOYLAN, OF CHICAGO, ILLINOIS, ASSIGNOR OF ONE-HALF TO GEORGE O. HOWARD, OF CHICAGO, ILLINOIS.

RECEPTACLE-LOCK-CONTROLLING DEVICE.

1,085,962.

Specification of Letters Patent.

Patented Feb. 3, 1914.

Application filed November 6, 1912. Serial No. 729,715.

To all whom it may concern:

Be it known that I, GEORGE W. BOYLAN, a citizen of the United States, residing at Chicago, in the county of Cook and State 5 of Illinois, have invented certain new and useful Improvements in Receptacle-Lock-Controlling Devices, set forth in the following specification, reference being had to the accompanying drawings, forming a part 10 thereof.

The purpose of this invention is to provide a box or receptacle with a spring lock or catch and with means which will prevent the locking of the box except under certain 15 predetermined conditions.

It consists of the features and elements shown in the drawings and described hereafter as indicated by the claims.

In the drawings: Figure 1 is a sectional 20 elevation of a box provided with devices embodying this invention. Fig. 2 is a detail elevation of certain parts shown in Fig. 1, being taken as a section at line 2-2 on Fig. 1. Fig. 3 is a detail elevation of a 25 modification which might be substituted for the parts shown in Fig. 2. Fig. 4 is a detail elevation of another modification applicable to the purposes of this invention.

The receptacle illustrated in the drawings 30 is specifically designed to be affixed outside the door of a dwelling for receiving groceries and other packages which may be delivered in the absence of the occupants, or at least without the necessity of calling 35 the occupants to the door to receive the goods. As shown, the box is particularly designed to receive milk bottles which would ordinarily be delivered quite early in the morning and would not be taken in for use 40 for several hours, and for this reason the box is provided with heat insulated walls, shown simply as double walls, A, provided 45 with a dead-air space, A¹, between them. The hinged cover, A², is furnished with a spring lock, B, which may be of any usual type having a spring protruded latch, B¹, adapted to engage a hasp or other abutment, A³, mounted on the front wall of the 50 box for locking the cover. It will be understood that this lock is releasable when the latch, B¹, is engaged with the hasp, A³, only by means of a suitable key, not shown. Thus ordinarily the cover, A², would become locked whenever shut down and could 55 only be unlocked by means of the key. To

prevent such locking when the cover is shut down while the box is empty, there is mounted preferably on the inner front wall a bell crank lever, C, whose longer arm, C¹, protrudes above the top edge of said front 60 wall at, C², so as to prevent the complete closing of the cover, A², and thus prevent the engagement of the latch, B¹, with the hasp or abutment, A³. Fig. 2 shows the lever in position for accomplishing this and 65 Fig. 1 indicates the resulting position of the cover, A². The shorter arm, C³, of the lever carries a stud, C⁴, which supports the free edge of a movable inner wall shown as a hinged false bottom, A⁴, while a spring, C⁵, 70 serves to counteract the weight of the bottom, A⁴, maintaining the parts in the position shown in Fig. 1. As soon as a bottle of milk or other package is deposited in the box, however, its weight acting upon the 75 hinged bottom, A⁴, will move the lever, C, to the position shown in dotted lines in Fig. 2, thus swinging the portion, C², below the upper edge of the front wall and permitting the cover, A², to be closed down to 80 a position in which the lock, B, will operate to secure it. Thus the goods are secured against theft or other interference as soon as delivered, and incidentally by virtue of the heat insulated walls of the box, will be 85 kept at practically uniform temperature for several hours.

Fig. 3 illustrates a modification of the invention in which a sliding bar, A⁶, is substituted for the permanently fixed hasp or 90 abutment, A³, shown in Fig. 2, and is connected for movement by the bell crank, C⁶, the latter being controlled by the false bottom, A⁴, in the same manner as above described. The slide bar, A⁶, is mounted for 95 movement past a recess, A⁷, in the front wall of the box, so that when positioned to span this recess it completes a rectangular opening similar to the opening, A⁸, in the hasp, A³, adapted to receive the latch member, 100 B¹, of the lock. Guide straps, A⁸, mounted at either side of the recess, A⁷, furnish a suitable support for the slide bar, A⁶, while a stud, A⁹, engaging a slot, A¹⁰, serves for further guidance of the bar when it is withdrawn as shown in Fig. 3, as is normally the case when the box is empty. With this form of the device it will be seen that the cover, A², is at no time hindered from being 105 completely closed, but except when the 110

added weight of a milk bottle or other goods is present on the hinged bottom, A⁴, the slide bar, A⁵, is withdrawn so as not to engage the latch, B¹, and the box cannot become locked.

A further modification is illustrated in Fig. 4, in which the opening in the hasp plate, A³, is arranged to be closed by a vertical slide bar, C¹⁰, having a stud, C¹⁴, at its lower end positioned to support the false bottom, A⁴, and provided with a spring, C¹⁵, which operates to counteract the weight of the bottom, A⁴, and retain the bar, C¹⁰, in position, shown in Fig. 4. It will be understood that the surface of the bar, C¹⁰, will lie flush with the surface of the plate, A³, or else will project above said surface so that the locking edge, A¹³, of said plate will not be available for engagement of the latch, B¹, and when the box is empty the cover may be closed but will not become locked. Added weight on the false bottom will serve, however, to retract the slide bar, C¹⁰, thus forming an opening bounded on one side by the locking edge, A¹³, of the plate, A³, into which the latch, B¹, may be protruded by its spring for securing the cover.

I claim:—

30. 1. A receptacle comprising a cover and a lock for securing the same, said cover being movable to a partially closed position for shielding the cavity of the receptacle, and movable to another position for effecting engagement of said lock, a movable inner wall, and means operatively connected thereto adapted to engage said cover at its partially closed position for blocking its movement to locking position.
35. 2. A receptacle comprising a cover and a

lock for securing the same, a movable abutment normally projecting from one edge of the receptacle and permitting movement of the cover to a position shielding the receptacle cavity, and a yieldingly movable inner wall connected with said abutment and adapted to withdraw the latter for permitting complete closure of the cover and engagement of the lock for securing the same.

3. A receptacle comprising a cover and a lock for securing the same, an abutment pivotally mounted upon a wall of the receptacle and dimensioned to project beyond the edge of said wall for holding the cover out of locking position, a yieldingly movable inner wall, and means connecting said wall to said abutment whereby the movement of said wall is adapted to swing said abutment away from its protruding position to permit the locking of the cover.

4. In a receptacle having a cover and a lock for securing the same; a bell crank lever fulcrumed upon a wall of the receptacle with one arm normally projecting above the edge of said wall for holding the cover out of locking position, said receptacle having a yieldingly compressible bottom and means connecting said bottom to the other arm of the lever for rocking the same when the bottom is depressed to swing the first mentioned arm away from its protruding position to permit the locking of the cover.

In testimony whereof I have hereunto set my hand at Chicago, Illinois, this 4th day of November, 1912.

GEORGE W. BOYLAN.
